UNITED STATES PATENT OFFICE.

JAMES CLERK MAXWELL GARNETT, OF MANCHESTER, ENGLAND.

DESIGN FOR A FLAG.

55,034.

Specification for Design.

Patented May 4, 1920.

Application filed November 8, 1919. Serial No. 336,746. Term of patent 7 years.

To all whom it may concern:

Be it known that I, JAMES CLERK MAXWELL GARNETT, a subject of the King of Great Britain, residing at Manchester, in the county of Lancaster, England, have invented a new, original, and ornamental Design for Flags, of which the following is a specification, reference being had to the accompanying drawing, forming part thereof.

The figure is a plan view of a flag, showing my new design.

I claim:

The ornamental design for a flag, as shown.

In testimony whereof I have hereunto set my hand in presence of two subscribing witnesses.

JAMES CLERK MAXWELL GARNETT.

Witnesses:
